tion of Delaware

Original application December 31, 1936, Serial No.
118,525. Divided and this application Novem-
ber 15, 1937, Serial No. 174,554

9 Claims. (Cl. 178—33)

This invention relates to printing telegraph apparatus, and particularly to selector mechanisms for controlling the operation of such apparatus.

This application is a division of application Serial No. 118,525, filed December 31, 1936 by W. J. Zenner which matured into U. S. Patent 2,228,716, granted on Jan. 14, 1941.

An object of this invention is to provide a selector mechanism of the assisted armature type in which the energy required to be developed by the selector magnet is minimized.

A feature of the invention is to provide a universally adjustable mounting for the selector magnet of a selector mechanism.

Another feature of the invention is to provide completely resilient interconnection between the armature assisting lever and the selector lever in a selector mechanism.

The invention contemplates numerous other features capable of incorporation into selector mechanisms in various combinations.

For a full and complete understanding of selector mechanisms of the type to which the several features of the invention may be applicable, reference may be had to Patent No. 1,937,376 granted November 28, 1933, to Walter J. Zenner.

Briefly stated, the invention contemplates that the armature of a selector magnet may be detached and dissociated from the armature assisting lever, and may instead be applied to a latch which has a shoulder to engage a lug formed on the armature assisting lever or may be applied directly to a selector lever which is movable under the control of the armature lever.

In an alternative embodiment of the invention, the selector magnet armature is fixed to the selector lever which the magnet may develop insufficient energy to attract, and the movement of which is controlled by the armature assisting lever.

For a complete understanding of the invention, reference may be had to the following detailed description, taken in connection with the accompanying drawing, in which—

Fig. 1 is a plan view showing a selector mechanism in which the selector magnet controls a latch for the armature assisting lever;

Fig. 2 is a vertical sectional view taken on the line 2—2 of Fig. 1;

Fig. 3 is a fragmentary elevational view of the selector mechanism of Fig. 1 as seen from the upper edge thereof;

Fig. 4 is a fragmentary plan view showing a selector mechanism in which periodic movement of the armature assisting lever is not affected by the operation of the magnet armature; and

Fig. 5 is a vertical sectional view taken on the line 5—5 of Fig. 4.

Referring now to the drawing in which iden-

tical reference characters designate corresponding parts throughout the several views, and particularly to Figs. 1 and 2, reference numeral 21 designates a mounting plate for a selector mechanism 5 for printing telegraph apparatus. A selector magnet assembly indicated generally by the reference numeral 22 comprises a bracket 23 to which is secured, by means of screws 24, a magnet core 26. Core 26 has two arms, each of which supports a winding 27 which is adapted to be connected to a telegraph line. At their outer ends the arms of core 26 terminate in pole faces 28.

Bracket 23 supports opposed pivot screws 29, 15 which in turn pivotally support a bell crank lever 31, one arm of which carries selector magnet armature 32, and the other arm of which terminates in a latching shoulder 33. Magnet bracket 23 has a depending boss 34 which, in addition to mounting the lower pivot screw 29 for the latching bell crank 31, extends through a close fitting aperture mounting plate 21 and establishes a center of rotation for selector magnet bracket 23. The bracket 23 is provided with arcuate apertures 36, the arcs of which have their centers on the axis of boss 34, and through which extend clamping screws 37 to threadedly engage mounting plate 21. At a point remote from boss 34 bracket 23 threadedly supports the shank of an adjusting screw 38 which is provided 25 with head 39, and, spaced therefrom along the shank, flange 41. A stud 42 is rigidly secured to mounting plate 21, and extends upwardly into the space between head 39 and flange 41. Screw head 39 may be provided with the usual slot 30 (not shown) for cooperation with a screw driver, and there may be provided in the periphery of the head, sockets 43 into which a pin may be inserted for rotation of screw 38 in the manner 35 in which capstans are rotated. The sockets 43 permit rotation of screw 38 by suitable implement when the installation of the selector mechanism is such as to prevent access to the slotted head by a screw driver.

It will be apparent that when screw 38 is rotated, it can undergo no axial movement, due to the confining action of head 39 and flange 41 upon stud 42. Since screw 38 threadedly engages bracket 23, the latter must move toward or away from stud 42 as the screw is rotated, and in so moving it pivots upon boss 34 and varies the air gap between pole faces 28 and armature 32.

An armature assisting lever 44 pivoted by means of screws 46 on bracket 47 secured to mounting plate 21 is disposed in operative alignment with an armature assisting cam 48 included in a selector cam assembly, indicated generally by the reference numeral 49, mounted on power driven shaft 51 extending through mounting plate

21. Cam assembly 49 is arranged to be driven from shaft 51 through discs 52 fixed to shaft 51, resilient discs 53 in frictional engagement with discs 52, and discs 54 fixed to cam assembly 49 and in frictional engagement with discs 53. Discs 52, 53, and 54 constitute friction clutch assemblies. Selector cam assembly 49 includes a stop arm 56 which is arranged to be arrested and released for rotation alternatively under the control of a stop gate 57 included in a stop gate assembly 58. Stop gate assembly 58 has as its foundation a plate 59 pivoted below a plate 61 by means of pivot screw 62 carried by plate 61 which is secured by screws 63 to posts (not shown) mounted on mounting plate 21. An arm 64 mounted on pivot screw 62 above plate 61 has extending therethrough the shank of a knurled-headed screw 66 which threadedly engages stop gate mounting plate 59. Plate 59 may be adjusted rotationally about pivot screw 62 and may be clamped in any desired position of adjustment by drawing plate 59 and arm 64 into clamping engagement with plate 61 by means of screw 66.

Stop gate 57 is pivotally mounted on post 67 carried by plate 59, has a portion disposed in the path of stop arm 56, and may be latched in that position by shouldered latch lever 68. Lever 68 is pivotally mounted on the under side of plate 59 and is urged by spring 69 into latching engagement with stop gate 57. Latch lever 68 is rocked against the resistance of compression spring 69 to lift its shoulder out of latching engagement with the stop gate by a plunger pin 71 in the operating path of which is disposed one arm of a bell crank 72, the other arm of which engages latch lever 68. A plunger operating screw 73 carried by extension 74 of armature lever arm 44 in alignment with plunger pin 71 shifts the pin to rock bell crank 72, which, in turn, rocks latch lever 68 and effects the release of the stop gate when the armature lever is in its extreme clockwise position. Plunger pin 71 is retracted by spring 69 and permits latch lever 68 to latch stop gate 57 when armature assisting lever 44 is in its extreme counterclockwise position.

Armature assisting lever 44 is shown in Fig. 1 in its extreme counterclockwise position. In moving into this position, it rocks bell crank 31 into its extreme clockwise position through engagement with yieldable compression spring 76 associated with bell crank 31. Armature 32 is thus brought into engagement with pole face 28. Armature assisting lever 44 has a lug 77 so disposed in relation to shoulder 33 of lever 31 that when levers 44 and 31 are in their counterclockwise and clockwise positions respectively, shoulder 33 is in blocking relation to lug 77. Cam 48 periodically rocks lever 44 into its counterclockwise position, and if magnet 27 is energized and holds armature 32 in opposition to biasing spring 78 of bell crank 31, shoulder 33 will hold armature assisting lever 44 in opposition to its biasing spring 79 after cam 48 has rotated sufficiently to remove an apex from engagement with lever 44 and to present a nadir portion thereto. If magnet 27 is not energized, spring 78 withdraws lever 31 from latching engagement with armature assisting lever 44, and spring 79 rocks lever 44 to its clockwise position when a nadir portion of the cam is presented to lever 44.

A selector lever 81 is pivotally supported by screws 82 carried by a mounting bracket 83 secured to mounting plate 21. A tension spring 84 has one end connected to selector lever 81 and

10 the other end secured to extension 85 of armature assisting lever arm 44. Extension 85 also carries an abutment screw 87 which is adjustable with respect thereto, and the head of which abuts selector lever 81 intermediate its ends. At its free end, which is the right-hand end as viewed in Fig. 1, selector lever 81 is provided with spaced depending arms 88, by means of which the setting of selector elements of a sword and T-lever selector assembly is controlled.

15 The sword and T-lever assembly is designated generally by the reference numeral 91, and comprises a plurality of thin, flat selector fingers, or sword levers 92, and an equal number of T-levers 93 individually aligned with the sword levers 92. Sword levers 92 are individually supported by spacer plates 94 which also separate the T-levers 93 and which are mounted on studs 95. Each of the sword levers 92 has at its left-hand end, as viewed in Fig. 1, a disc-like portion 97 which is fitted into a correspondingly shaped aperture in a sword operating bell crank lever 98 pivotally mounted on pivot pin 99. Each of the bell crank levers 98 is arranged to be rocked counterclockwise by one of a plurality of cam projections 101 carried by the cam assembly 49 in helical arrangement. Adjacent to the disc-like portion 97 each sword lever 92 is provided with oppositely extending arms 102 which terminate in abutments 103.

20 T-levers 93 are rotatably mounted upon pivot pin 104 carried by mounting plate 21 and each of the levers 93 is provided with an arm 105 which terminates in a disc-like portion 107. T-levers 25 93 are intended to be articulated, by means of the disc-like portions 107, to code bars, code discs, or other permutation code elements (not shown) as disclosed in Patent No. 1,745,633 granted February 4, 1930, to S. Morton et al.

30 35 40 Pivot pin 99, in addition to supporting sword lever operating bell cranks 98, also pivotally supports a locking bell crank lever 108 which has one arm 109 terminating in a cam follower portion which engages a locking cam 111, included in cam assembly 49, and has another arm 112 terminating in a locking blade 113 adjacent to which selector lever 81 is provided with a locking lug 114.

45 50 55 Selector lever 81 is adapted to be rocked, in a manner which will be described later, through an arc sufficient to bring one or the other of its arms 88 into the path of one or the other of abutments 103 of sword levers 92 as the sword levers are reciprocated leftwardly by associated bell cranks 98, and such angular movement of selector lever 81 is sufficient to bring locking lug 114 from one side to the other of locking blade 113. Continued reciprocation of a sword lever, after one of its abutments 103 has engaged one of the depending arms 88 of selector lever 81, causes the sword lever to move angularly about the center of its disc-like portion to bring its free end into engagement with its associated T-levers 93 at either side of the pivotal mounting 104 thereof. The angular movement of sword levers 92 is limited by stop pins 116 carried by mounting plate 21. Sword lever bell cranks 98 and locking bell crank 108 are biased clockwise and counterclockwise respectively, by tension springs (not shown).

60 65 70 75 The selector mechanism shown in Figs. 1 and 2 is adapted to be controlled by permutation code signals comprising marking and spacing impulses in various combinations received by the selector magnet winding 27 from the telegraph line to

which it is connected. When the selector mechanism is not operating and is responding to a stop impulse, which is of marking nature and is manifested by energized condition of selector magnet 21, armature 32 is held to pole face 28, latch lever 31 engages lug 71 of armature assisting lever 44 and holds that lever in its extreme counterclockwise position out of engagement with cam 48, which, in the rest condition, presents a nadir portion to lever 44, and abutment screw 73 is drawn away from plunger pin 71, which, being retracted, causes stop gate 57 to be latched to hold cam assembly 49 motionless. When a code signal combination is received, the first impulse thereof is the start impulse which results in deenergization of the selector magnet and permits spring 78 to rotate latch lever 31 counterclockwise, thus releasing lever 44 which rocks into engagement with cam 48 and depresses plunger pin 71, whereby stop gate 57 is released from latch lever 68. Cam assembly 49 rotates through one revolution during the reception of a code combination, and, in rotating, cam 48 rocks armature assisting lever 44 counterclockwise, cam 111 unlocks selector lever 81, these operations occurring periodically, and cam projections 101 rock sword lever bell cranks 98 counterclockwise successively. All of these operations occur in timed relation to the reception of code signal impulses. If the selector magnet is energized at the instant armature cam 48 actuates armature assisting lever 44 to bring armature 32 into engagement with pole face 28 and lever 31 into latching engagement with lug 71, the armature will be held and latch lever 31 will hold armature assisting lever 44 in its extreme counterclockwise position in opposition to tension spring 77, whereby abutment screw 87 will be drawn away from selector lever 81. Upon the unlocking of selector lever 81, tension spring 84 will cause the lever to be rotated to its extreme counterclockwise position, whereby one of the arms 88 will be presented to an abutment 103 of a particular sword lever 92 to effect the setting of the sword lever in accordance with the energized condition of the selector magnet. When the selector magnet is deenergized at a time that armature 34 is brought into engagement with pole face 28 by armature assisting cam 48, the armature will not be held, latch lever 31 will not hold lever 44, which will return to its extreme clockwise position, and the selector lever, when unlocked, will be positioned in accordance with the deenergized condition of the selector magnet.

A code signal combination concludes with a stop impulse which is represented by the energized condition of the selector magnet. The armature is thus held, and armature assisting lever 44 is retained in its extreme counterclockwise position by latch lever 31, whereby plunger pin 68 is permitted to be retracted by spring 69, and stop gate 57 is locked. It follows from this that cam assembly 49 is arrested at the conclusion of one revolution and, with a nadir portion presented to latched lever 44, awaits release by the start impulse of the next code signal combination.

The selector mechanism hereinbefore described has the advantageous feature that winding 21 is required to carry only sufficient energizing current to cause armature 32 to be held in opposition to tension spring 78. None of the stored energy of armature assisting lever restoration spring 79 is operative upon armature 32, but

is instead resisted by latching shoulder 33 which has positive blocking relation to latching lug 71 until the selector magnet releases its armature. The use of low transmitting potentials is thus made possible.

Another embodiment of the invention, in which a different relationship between armature assisting lever, selector lever, and magnet armature exists, is shown in Figs. 4 and 5. Referring now to those figures, it will be noted that a selector mounting plate 121 supports a selector magnet assembly 122 and brackets 123 and 124 on which selector lever 126 and armature assisting lever 127 are respectively pivotally mounted by means of pivot screws 128 and 129, respectively. Armature assisting lever 127 is urged into extreme clockwise position by tension spring 131 and is periodically rocked counterclockwise by armature assisting cam 132 included in selector cam assembly 133 carried by power-driven shaft 134. The armature of the selector magnet is designated 136 and is mounted directly on selector lever 126, which has, at its free end, locking lug 137 similar to that employed on selector lever 81 (Fig. 1) with which there cooperates locking bell crank lever 138 which is biased counterclockwise by spring 135, and is periodically rocked by cam 140. Since selector lever 126 carries the selector magnet armature 136, the tripping of the stop gate for the selector cam assembly 133 in response to a start impulse must be under the control of that lever. Accordingly, lever 126 is provided with an arm 139 having abutment screw 141 in operative alignment with stop gate latch tripping plunger pin 142 of adjustable stop gate assembly 143, a fragment only of which is shown in Fig. 4, but which may be similar to the stop gate mechanism shown in Figs. 1 and 2.

The interconnection between selector lever 126 and armature assisting lever 127 is shown in detail in Fig. 5 by reference to which it will be observed that selector lever 126 is provided with spaced depending arms 144 in alignment with which are depending arms 146 of armature assisting lever 127 spaced apart a greater distance than are the arms 144. The arms 147 of selector lever 126 are apertured to receive shouldered pins 147, which are urged in opposite directions by compression spring 148 to force their outer ends into abutting relation with the inner surfaces of arms 146. With the arrangement shown in Figs. 4 and 5, selector lever 126 tends to be centered with respect to armature assisting lever 127, and if the latter is moved angularly, an unbalance is created in the combination of pins 147 and spring 148 which causes the selector lever 126 to be moved in a direction to eliminate the unbalance when it is unlocked by locking bell crank 138. It will be observed that the interconnection between armature assisting lever 127 and selector lever 126 is resilient or permissive in both directions, as contrasted with the interconnection shown in Figs. 1 and 2, comprising a tension spring and an abutment screw, the combination of which affords a permissive or resilient interconnection in one direction, and a positive interconnection in the other direction.

In the operation of a selector mechanism, as disclosed in Fig. 4, it will be presumed that the energizing current of the selector magnet produces enough magnetic attraction to hold selector lever 126 in opposition to a condition of unbalance in the spring interconnection between selector lever and the armature assisting lever,

but which is insufficient to attract the selector lever from its extreme clockwise to extreme counterclockwise position. Due to the periodic rocking of armature assisting lever 127 counterclockwise by cam 132, an unbalance, tending to rotate selector lever 126 counterclockwise, will be generated in the interconnecting pins 147 and spring 148, and when locking bell crank 138 is actuated by cam 149 to unlock selector lever 126, the latter will be rotated to bring armature 130 into engagement with the pole face of the selector magnet 122. If the magnet is then energized, the selector lever 126 will be held in its extreme counterclockwise position after the armature assisting lever 127 has returned to its extreme clockwise position due to escapement of its cam follower portion from an apex of cam 132, and a selective condition corresponding to a marking signal is thus established, whereupon locking bell crank cam 149 permits locking bell crank 138 to lock lever 126.

If instead of being energized at the time the armature assisting lever 127 is rotated counterclockwise, the selector magnet should be deenergized, in response to a spacing signal, the selector lever 126 will not be held and will return to its extreme clockwise position when the armature assisting lever returns to its extreme clockwise position, whereupon the selector lever may be locked in that position, which corresponds to a spacing signal condition of the selector magnet.

With the arrangement shown in Figs. 4 and 5, the selector magnet armature is not associated with the armature assisting lever, but is associated with the selector lever. The selector magnet is not called upon to actuate selector lever 126, nor to hold it in opposition to the relatively strong restoring spring 131, but is only required to hold it in opposition to a relatively weak unbalance in the centering spring mechanism when the armature lever returns to its extreme clockwise position. The restoring spring for the armature assisting lever may thus be as heavy as desired. Furthermore, the armature assisting lever is never held out of engagement with the armature cam, as it may be in the structure shown in Fig. 1, by latch lever 34, but is instead continuously responsive in its movements to the contour of the armature cam.

Although particular embodiments of the invention have been shown and described herein, it is to be understood that the invention is not to be interpreted as being limited to the specific details shown and described, but is capable of modification and rearrangement within the scope of the appended claims.

What is claimed is:

1. In a selector mechanism, a group of selectors, an electromagnet, an armature for said electromagnet, an element through which said armature is moved toward said electromagnet periodically, and means operated by the electromagnet for holding or releasing said element, a selector lever presentable in either of two positions according to whether said element is held or released, and means for positioning said selectors according to the successive positions of said selector lever.

2. In a selector mechanism, an electromagnet, an armature therefor, an element to be actuated periodically having a portion to control said armature and another portion to be controlled by said armature, and means for effecting the periodic operation of said element.

3. In a selector mechanism, an electromagnet, an armature therefor, said electromagnet adapted

to exert a predetermined attractive force upon the armature when energized, a periodically movable element, a cam for effecting periodic movement of the element, a spring cooperating with said element to urge it into engagement with said cam, said spring exerting a materially greater force than the attractive force of said magnet, and means controlled by said magnet for withholding said element from engagement with the cam in opposition to said spring.

4. In combination, an electromagnet, an armature therefor, a power driven cam, an armature controlling member actuated periodically by said cam, a biasing spring for establishing cooperation between said cam and said member, and means associated with said armature for holding said member out of cooperation with said cam without opposing said biasing spring to the attractive force of said electromagnet.

5. In a selector mechanism, an electromagnet, an armature therefor, a selection controlling lever, a power driven cam for periodically rocking said lever, a spring for urging the lever into contact with said cam, means associated with said lever for bringing said armature into engagement with said electromagnet, and means effective upon energization of the electromagnet for holding the lever out of contact with said cam whereby the attracted armature is independent of the action of said biasing spring.

6. In an electro-responsive device, an electromagnet, a power driven cam, a pivoted lever having a portion engageable with said cam, a pivoted latch having a portion to receive movement from said lever and a portion to latch said lever against movement, and an armature for said electromagnet carried by said latch.

7. In an electroresponsive device, an electromagnet, a power driven cam, a pivoted lever having a portion engageable with said cam, a pivoted latch, a yieldable element associated with said latch and engageable by said lever for effecting pivotal movement of said latch, a projection carried by said lever to be engaged by said latch for holding said lever out of engagement with said cam, and an armature for said electromagnet carried by said latch for controlling the latch.

8. In an electroresponsive device, an electromagnet, an armature therefor, a latch lever by which said armature is supported, a leaf spring carried by the armature supporting arm of said latch lever, a power driven cam, a pivoted lever having a portion engageable with said cam and another portion engageable with said leaf spring for moving said armature into engagement with said electromagnet, a projection carried by said pivoted lever to be engaged by said latch for holding said pivoted lever out of engagement with said cam, and means effective upon the release of said armature by said electromagnet for restoring said pivoted lever to engagement with said cam.

9. In combination, an electromagnet, a pivoted lever, an armature for said electromagnet carried by said lever, a power driven cam, an armature controlling lever actuated periodically by said cam, a biasing spring for establishing cooperation between said armature controlling lever and said cam, and means carried by said pivoted lever and engageable with said armature controlling lever for rendering mutually independent the force exerted by said electromagnet upon its armature and the force exerted by said biasing spring upon said armature controlling lever.

WALTER J. ZENNER.
